UNITED STATES PATENT OFFICE

2,459,257

CHAIR, TABLE, AND DESK COMBINATION

Halbert M. Wood, Madison, Wis.

Application August 12, 1946, Serial No. 690,058

1 Claim. (Cl. 155—124)

1

This invention relates to a combined chair, desk and table combination, the primary object of the invention being to provide a chair, table and desk combination furniture wherein the frame thereof comprises removable sections from which the chair or seat, and table or desk, may be readily and easily removed or replaced.

Still another object of the invention is to provide a sectional frame, wherein the sections are held together by a chair seat or table and desk top, novel means being provided for removably connecting the frame sections.

With the foregoing and other objects in view which will appear as the description proceeds, the invention consists of certain novel details of construction and combinations of parts hereinafter more fully described and pointed out in the claim, it being understood that changes may be made in the construction and arrangement of parts without departing from the spirit of the invention as claimed.

Referring to the drawing

Figure 1 is a plan view of a chair, table or desk combination constructed in accordance with the invention.

Figure 2 is a side elevational view thereof, a portion of the desk or table having been broken away to illustrate the adjusting means used in adjusting the top of the table or desk.

Figure 3 is a sectional view taken on line 3—3 of Figure 2.

Referring to the drawing in detail, the chair, desk and table combination, comprises a frame embodying identical sections indicated generally by the reference character 5.

Each of these sections comprises a length of rod material, bent to provide base sections 6, the front ends thereof being extended upwardly as at 7 and rearwardly as at 8, from where they extend forwardly as at 9, the forwardly extended portion 9 being parallel with the base 6.

The portion of the frame section at the rear end of the base 6, extends upwardly as at 10 and forwardly as at 11, and then rearwardly as at 12, the portions 11 and 12 being disposed in parallel spaced relation with each other, the space between the portions 11 and 12 being equal to the thickness of the chair seat 13, which is adapted to be slipped therebetween.

A clamp indicated at 14 is secured to the seat

13 at each end thereof, the clamp 14 being designed to grip the forwardly extended portions 11 of the adjacent sections of the frame.

The portion 12 of the frame section as illustrated, extends upwardly providing the back supporting rod 15.

It will of course be understood that two of these sections are required in the formation of the frame of the device.

10 The sections are held in spaced relation with respect to each other, by means of the back 16 which is provided with tubular sections 17 that are adapted to fit down over the supporting rods 15 of the sections. Thus it will be seen that due 15 to this construction, the sections of the frame at the rear of the device, will be held in spaced relation with respect to each other.

16 The reference character 18 indicates the desk or table, which is box-like in formation, the upper 20 surface thereof being sloped downwardly toward the chair seat, to provide a comfortable writing surface.

Within the desk or table 18, is a tubular internally threaded member 19 which is secured at 25 a point, intermediate the side edges of the desk or table.

26 Fitted within this tubular member 19, is a threaded rod 20 which is formed with a head 21 adapted to engage the undersurface of the hinged 30 top 22 to elevate the top should it be desired to use the top as a table.

Secured to the undersurface of the desk or table 18, are horizontally disposed tubular members 23 that are held in position by means of 35 the straps 24. These tubular sections 23 are arranged adjacent to the side edges of the bottom of the desk or table 18, and are adapted to accommodate the forwardly extended ends 9 of the frame sections, thereby providing a support for the desk or table.

40 In order that the desk or table 18 will be held against movement with respect to the frame of the device, the straps 24 as well as the tubular members 23, are provided with registering openings, adapted to accommodate the bolts 25, whereby the various sections are held together at all times.

45 From the foregoing it will be seen that due to the construction shown and described, I have provided a chair, desk and table combination

embodying a frame which is constructed of separable sections, the sections of the frame being held together by means of the desk or table top used in connection with the frame. It will also be seen that the seat, which is indicated by the reference character 13, is held between the portions 11 and 12 of the sections, will also act to brace the frame.

What is claimed is:

A combined desk and chair comprising identical frame sections arranged parallel to each other, each frame section embodying a length of rod material constructed with upstanding ends to form a back and then bent forward at right angles therewith and then bent backward in a U shape to provide spaced parallel members, a seat held between the parallel members of the frame sections, said parallel members frictionally engaging the upper and lower surfaces of the seat, the rod at the lower rear end of the U shape then bent downward to form a rear leg for the chair, then forward to form a floor-engaging section, then upward to form a leg for the desk, then forward and terminating in a horizontal

section, a back member, vertical tubes secured to the back member into which the upper ends of the lengths of rod material are disposed, securing the back to the back section, the forwardly extended ends of the sections being fitted in tubes of a desk, securing the desk to the frame sections, at the front ends thereof.

HALBERT M. WOOD.
